UNITED STATES PATENT OFFICE.

HENRY NEWTON SHERBURNE, OF PLAQUEMINE, LOUISIANA.

SPEED BOAT.

Application filed July 14, 1924. Serial No. 725,932.

To all whom it may concern:

Be it known that I, HENRY NEWTON SHERBURNE, a citizen of the United States, residing at Plaquemine, in the parish of Iberville and State of Louisiana, have invented certain new and useful Improvements in Speed Boats; and I do declare the following to be a full, clear, and exact description of the invention, such as will enable others skilled in the art to which it appertains to make and use the same.

The present invention relates to improvements in speed boats and has for an object to provide a light craft susceptible of carrying relatively heavy weight at high speed in very shallow water without interference from marine growth such as water lilies.

Another object of the invention consists in the provision of an improved hull of improved formation in order to adequately sustain the weight of the motor and cargo without allowing the draft to become too great as to interfere materially with the speed of the boat and the bottom of the hull is co-ordinated in its construction with weight and disposition of weight of the motor to properly place the center of gravity and to offset both the weight of the motor and the propelling force thereof.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a side elevation of an improved speed boat constructed according to the present invention.

Figure 2 is a top plan view of the same.

Figure 3 is an end view of the boat.

Figure 4 is a bottom plan view.

Figure 5 is a transverse section taken on the line 5—5 in Figure 2, and

Figure 6 is a similar section taken on the line 6—6 also in Figure 2.

Referring more particularly to the drawings 7 designates generally the hull of the boat, 8 the motor and 9 the propeller which is an air propeller of large dimensions situated above the rear portion of the hull and for this reason the motor is elevated upon a stand constructed especially for the purpose, the stand being received upon the

longitudinal timbers 10 and 11 which run the full length of the hull and which are a part of the hull construction as shown in Figures 5 and 6, these timbers reinforcing and strengthening the hull in a longitudinal direction and to opposite sides of the longitudinal center of the hull at equally spaced distances, so as to balance not only the hull in the water, but also the motor upon the timbers.

At the rear portion of the hull these timbers are of sufficient height to project above the rear deck 12, but at the front portion of the boat as shown in Figure 5 the timbers lie beneath the convex deck 13.

In Figure 2 the cock pit is shown at 14 for receiving the seat for the passengers and the controls for the rudder and motor.

The boat is steered by means of the rudder 15 pivotally suspended as indicated at 16 from the vertical rod 17 forming a portion of the rudder gear which is held in appropriate brackets 18 upon the end of the boat. The rod 17 is spread at its lower ends into forks 19 which embrace the side portions of the rudder and carry a pin 20 pivoting through a slot 21, of the rudder blade in order to permit the blade to swing in a vertical plane, although the weight of the rudder will normally hold it down somewhat beneath the flat bottom of the boat. In passing over obstacles as water lilies and the like in the water the rudder 15 may rise to the dotted line position shown in Figure 1 so as to avoid any breakage in the rudder blade or its parts.

The hull is wide as compared with its length in order to give stability to the boat, especially with the elevated motor and propeller which weighs considerably and the bottom of the hull is divided into front and rear sections which are separated by the step 22; this step occurring about midway of the length of the boat and extending in a transverse direction. The front section of the bottom is composed of half portions 23 and 24 shown in Figure 4 which half portions slope in opposite directions from the keel line 25 upwardly toward the outer edge of the hull and at the same time these hull sections are curved, as indicated in Figure 1 from a high point at the bow gradually downward toward the stern, this curvature being indicated at 26 and moreover as shown in Figure 4 the bow is pointed in the usual

manner so that the outer edges of the bottom sections 23 and 24 converge forwardly while at the convergent edges the bottom sections are rounded as indicated at 27 in Figure 4 from the substantially horizontal plane of the bottom to the substantially vertical plane of the side of the boat.

The rear section of the bottom is composed of portions 28 and 29 which extend on a slight inclination from a high point at the step 22 downwardly toward the rear end of the boat and these portions 28 and 29 also slope transversely from the keel line outwardly and upwardly to the sides of the boat. In Figure 5 is shown the transverse inclination given the front sections 23 and 24 and in Figure 6 the inclination given the sections 28 and 29 is clearly illustrated.

The boat is relieved of any longitudinally continuous keel and instead a small metal keel 30 is provided upon the rearmost portion of the front bottom section just in advance of the step 28 while a similar keel 31 is carried by the rearmost central part of the rear bottom section at approximately the stern of the boat, this keel 31 being raised above the intermediate keel 30 because of the stepping of the bottom sections. Both keels are short in length and have inclined outer ends to assist in dividing the water. The rear bottom section is also provided with lateral balancing keels 32 and 33 similar to the keel 31 and being located at the outer edges of the rear bottom portions 28 and 29 and consequently slightly raised with respect to the keel 31.

The engine 8 is supported upon end and intermediate standards 34 and 35 which are reinforced by diagonal crossed braces 36 and 37 intersecting at approximately the center of the intermediate standard 35 and being riveted, welded or otherwise secured thereto. The outer ends of the crossed braces 36 and 37 are secured respectively to the upper and lower ends of the end standards 34. A top rail 38 connects the upper ends of the standards and the lower ends of the several standards are secured appropriately to the upper projecting edges of the timbers 10 and 11 which as before stated extend above the rear deck 12. The intermediate standards 35 are placed slightly forwardly of the rear section of the bottom in order that the center of gravity may cause the boat to assume a proper position in the water with the bow slightly raised. The weight of the cargo and passengers is also forwardly of the motor stand so that the motor must be placed forwardly to take care of this additional weight. Moreover the propulsive force of the propeller 9 will tend to drive the bow downwardly into the water and the weight of the motor and its position upon the relatively shallow flat bottomed hull compensates for this action.

In operation the motor is started and is provided with well known controls accessible to the operator occupying the seat 14 in the cock pit. The motor drives the propeller 9 which reacts against the surrounding air and drives the boat. Inasmuch as the body takes only a very light draft, the air propeller will be capable of driving it at great speed and as the speed increases the boat will tend to rise proportionately out of the water so that the skin friction will be reduced in ratio to the speed permitting of the attainment of the very high speed. Moreover the disposition of the weight of the motor with reference to the character and formation of the double flat bottom section admits of lifting the bow of the boat and in fact substantially the entire boat from the water with only the two keels 30 and 31 and the rudder being immersed in the water during the highest speed of the boat.

The inclination given both bottom sections tend to raise the boat when driven forwardly and the flat character of the boat together with the position of the motor prevents the bow being driven out as would otherwise occur from the tendency developed by the propeller 9. The step 22 admits air and tends to break any vacuum that would occur upon the bottom of the boat and this is also assisted by the lateral inclination of the sections which assists in raising the bottom of the boat as it gathers speed.

It is obvious that various changes and modifications may be made in the details of construction and design of the above specifically described embodiment of this invention without departing from the spirit thereof, such changes and modifications being restricted only by the scope of the following claims.

What is claimed is:-

1. A speed boat comprising a hull having a substantially flat bottom made up of sections stepped one above another, the sections being sloped from front downwardly to stern and being inclined laterally from the keel line in an outwardly and upper direction, short keels carried by the rear portions of the front and rear sections, said front section being curved at its forward end and curved to the bow of the boat, and a motor and propeller erected at an elevation above substantially the intermediate portion of the rear section of the bottom.

2. A speed boat comprising a hull of relatively short yet wide surface area made up in two sections, the rear section being stepped above the plane of the front section, each section composed of half portions inclined from the keel line outwardly and upwardly in lateral directions and both said sections inclining from their forward ends downwardly toward the rear ends, said front section being curved from the high

point at the bow downwardly toward the rear portion and having convergent and curved forward edges, longitudinal timbers to opposite sides of the longitudinal center line of the boat above the bottom sections, an engine frame mounted on said timbers substantially midway of the bottom section, and an air propeller driven by said engine.

3. A speed boat comprising a hull of relatively short yet wide surface area made up in two sections, the rear section being stepped above the plane of the front section, each section composed of half portions inclined from the keel line outwardly and upwardly in lateral directions and both said sections inclining from their forward ends downwardly toward the rear ends, said front section being curved from the high point at the bow downwardly toward the rear portion and having convergent and curved forward edges, and front and rear closed decks respectively above the two bottom sections with an open cock pit between these sections, longitudinal timbers extending substantially the length of the hull and being set on end, said timbers extending above the rear deck, an engine frame mounted on the projecting parts of the timbers at the rear part of the boat with the center of gravity above substantially the center of the rear portion of the bottom, an engine and a propeller carried by said frame and a pivoted rudder at the rear of the boat.

the rear section, an engine and a propeller supported thereon.

4. A speed boat comprising a hull of relatively short yet wide surface area made up in two sections, the rear section being stepped above the plane of the front section, each section composed of half portions inclined from the keel line outwardly and upwardly in lateral directions and both said sections inclining from their forward ends downwardly toward the rear ends, said front section being curved from the high point at the bow downwardly toward the rear portion and having convergent and curved forward edges, and front and rear closed decks respectively above the two bottom sections with an open cock pit between these sections, longitudinal timbers extending substantially the length of the hull and being set on end, said timbers extending above the rear deck, an engine frame erected on the projecting parts of the timbers at the rear part of the boat with the center of gravity above substantially the center of the rear portion of the bottom, an engine and a propeller carried by said frame and a pivoted rudder at the rear of the boat.

HENRY NEWTON SHERBURNE.
